Fig. 1

Fig. 2

Fig. 3

FIG. 1 is a side elevational view of a sport shoe embodying my new design;

FIG. 2 is a front perspective view of the sport shoe; and

FIG. 3 is a rear perspective view of the sport shoe.

The opposite side of the shoe shown in FIG. 1 is substantially the same in appearance as the side that is shown.

The characteristic feature of my design resides in the foxing tape portion of the sport shoe design, all as shown on the drawing.

This is a division of my design application Ser. No. 282,052 filed Aug. 21, 1972.

I claim:

The ornamental design for a sport shoe, substantially as shown and described.
